UNITED STATES PATENT OFFICE.

JACOB SCHAUB AND JACOB N. LARSEN, OF LOGAN, UTAH, ASSIGNORS, BY DIRECT AND MESNE ASSIGNMENTS, TO WESTERN BOOK AND MANUFACTURING COMPANY, OF LOGAN, UTAH, A CORPORATION OF UTAH.

BINDER-FRAME FOR LOOSE-LEAF BOOKS.

No. 921,467.

Specification of Letters Patent.

Patented May 11, 1909.

Application filed October 17, 1906. Serial No. 339,333.

To all whom it may concern:

Be it known that we JACOB SCHAUB and JACOB N. LARSEN, both citizens of the United States, residing at Logan, in the county of Cache and State of Utah, have invented a certain new and useful Binder-Frame for Loose-Leaf Books, of which the following is a specification.

Our invention consists of means for binding loose leaves, or the like, between the covers of a book, or similar inclosure, including record books, ledgers, account books, etc.

In the keeping of record and account books, modern business methods contemplate the use of separate or individual sheets or leaves, usually typewritten, adapted to be subsequently bound into a book or volume; such typewritten record or account sheets being preferred for many reasons, among them being the greater legibility of the writing; the saving in space, time and labor; and the decrease in the cost of preparing the record and the charges and space for storing such records or accounts.

The object of our invention is to provide means for binding such individual sheets, typewritten or otherwise, in a secure, compact and durable manner; the sheets or leaves being locked in place for greater security, whereby a permanent record is produced which cannot be tampered with or altered, a record of this character being especially desirable for legal, mercantile and other purposes.

The new binder of our invention possesses many advantages from a practical standpoint. It can be unlocked only by the proper key, and then opened for the ready introduction of additional leaves or pages, by the custodian of the key. All the parts are connected, in the sense that no one part is loose or detachable, thus overcoming the objection to the use of separable parts which may become lost or mislaid. The leaves or

pages are perforated by peculiar forms of holes, and they are threaded on certain parts in such a way as to minimize tearing the corners of the perforations. The device is simple and strong in construction, durable and efficient in service, and readily applied to the covers of a book so as to form a complete binder.

In the accompanying drawings we have shown one embodiment of the invention, but

the construction shown therein is to be understood as illustrative only, and not as defining the limits of the invention.

Figure 1 is a perspective view of the binder embodying our invention; Fig. 2 is a cross-section thereof, showing the binder in a closed position; Fig. 3 is a plan view on an enlarged scale, illustrating one member of the binder frame, the locking slide, and a locking contrivance for holding said slide against endwise movement; Fig. 4 is a side elevation of the complete binder frame; Fig. 5 is a detail longitudinal section on the line 5—5 of Fig. 3; Fig. 6 is a detail view of one member of the binder frame, the dotted line showing an adjusted position of the locking slide; Fig. 7 is a detail view of a portion of the binder frame, illustrating the hinge pintle for one of the page posts or links; Fig. 8 is a detail view of the member shown by Fig. 3, and the locking slide, said view representing a horizontal section through the locking contrivance; Fig. 9 is a section on the line 9—9 of Fig. 8; Fig. 10 is a detail perspective view of one of the page posts or links; Fig. 11 is a cross-section through one post or link; Fig. 12 is a detail view of a portion of a page or leaf, showing a new form of perforation therein; and Fig. 13 is a cross-section on the line 13—13 of Fig. 3.

In connection with the leaves or covers A, B, we employ a number of metallic parts which are adapted to be assembled, substantially as shown by Fig. 4, to produce what may be designated as a binder frame. Said frame consists of members C, D, a plurality of page posts or links E, and means on the respective members C, D, for locking the posts or links detachably to said members. The covers A, B, may be made of pasteboard, or any other material suitable for the purpose, and said covers are shown as being joined by a backing A', but the form or construction of the covers and the backing therefor may be modified within wide limits, without departing from the present invention. The members C, D, of the new binder frame are applied or secured to the respective covers A, B, in a manner to be hereinafter set forth, and the pages or leaves B' of the book or record are adapted to be threaded on the posts or links E. The member C or D consists of a flat piece or strip of metal, preferably sheet metal, such as sheet

brass, steel, or the member may be made of other appropriate material. Said member is of the required length and width to answer the purpose, and according to the invention one longitudinal edge of said member is doubled, folded or rolled upon itself to produce a guide, loop, or keeper, the latter being indicated at F. In one form of the invention the guide or keeper is curved in cross-section, substantially as shown by Fig. 13, although it will be understood that the particular form of the loop or keeper is not material. Said loop is cut away at intervals to produce a plurality of notches indicated at f, one of said notches being shown more clearly by Fig. 6 of the drawings. Said member, C or D, may be fastened or secured to one cover of the binder in any suitable or approved way, but, as shown more clearly by Fig. 3, the body portion of the sheet metal member is cut or punched to provide tongues g', the latter being integral with said plate or strip, and adapted to be bent at an angle thereto, whereby the plate member may be fitted laterally against the cover, and the prongs g' may be passed through and clenched against said cover, or embedded therein in a well known way for the purpose of securely attaching the member to said cover.

Any desired number of posts or links E may be used in connection with the members C, D, and the cover of the binder. It is preferred to provide each member, C or D, with a number of the slots or notches f in the keeper or guide F, Fig. 3 showing five of said notches. In Fig. 4, we have represented the binder frame as having a series of five transverse posts or links E extending across from one member to the other member, the posts E corresponding in number to the notches f in the respective members. We may, however, use only two of the posts or links E, and locate them at or near the end portions of the members, C, D, but it is evident that we may increase the number of links to three, four or five, or even more, as desired.

We construct each page or leaf B', and the posts E, in a manner peculiar to our invention, for the purpose of minimizing the tendency of the page or leaf to become torn at the corners of the perforations. It has been found by practical experience that if the page B' is provided with square perforations, the corners of which meet at right angles, the page or leaf has a tendency to very easily tear at the corners. We overcome this objection by providing each page with a perforation b, the corners b' of which are rounded or curved. Each link E is almost square or oblong in cross-section, as indicated by Fig. 11, but instead of having square corners on each post, we round or bevel said corners, as indicated at e in Fig. 11. Furthermore, we

prefer to make each end portion of the link or post of less width than the main body of the post, (see Figs. 5 and 10), the width of said end portion being equal to the length of one of the slots f in the keeper or guide F of the member. This reduction in the width of each end portion e³ of the post provides two shoulders e', and said reduced end portion e³ is provided with an eye e², said eye e² being at one side of the shoulders e'. Said shoulders are curved on their exposed faces, and, as will presently appear, these curved shoulders serve the purpose of guides in directing the sliding or endwise movement of the pintles which are provided on each locking slide.

It will be understood that the links or posts E are arranged between the members C, D, for the reduced end portion e³ of said posts to enter the notches f in the keepers or guides F of the respective members, the shoulders e' of said posts engaging squarely with said members C, D, for the purpose of assembling the parts compactly, and enabling them to engage firmly with each other. The eyes e² of the links or posts are in alignment or registration with the openings or spaces of the keepers or guides F on the members, and this relative arrangement of the eye-formed end portions of the posts to the keepers of the members enables the pintles G of the locking slides H to engage readily with said eye-formed end portions of the posts when said slides are moved in one direction.

The slide H is a single continuous piece of metal, preferably sheet brass or steel, although other materials may be employed, the length of said slide being about equal to the length of the member and each slide being quite narrow, the width of the slide being much less than that of the member with which it is associated. As shown by Figs. 3 and 7, each slide is formed at one longitudinal edge with a rolled, folded or doubled portion adapted to produce a web g, and, at intervals, the slide adjacent to its web portion and the pintles G, is slotted or recessed as at h, and is provided with notches or openings h'. The web g and the pintles G, are on the same side or edge portion of the slide, said web and the pintles being in alignment or registration with each other, although the web and the pintles are not continuous for the reason that they are interrupted or broken by the cut out portions h' of the slide. Any desired number of pintles G may be provided on the folded edge of the slide, but, as shown, said pintles correspond in number to the notches f in the keepers, and the number of posts or links E, which we prefer to employ. The pintles G extend lengthwise of the member, and alongside of the cut away portion h thereof. The slide is fitted laterally and compactly against one face or side

of its proper member, and it is confined slidably thereon for endwise movement by the web *g* and the pintles *G* fitting snugly in the space of the keeper or guide *F*. It is evident 5 that other expedients may be employed for confining the slides on the respective members, but we prefer the construction and arrangement herein shown and described, for the reason that it is quite simple and cheap, 10 and, furthermore, is efficient and reliable in service.

Although we have shown and described the locking slide as being doubled or folded upon itself at one of its edges, it is evident that we 15 may employ a metallic piece which is rolled to the required form or shape, the pintles *G*, and the webs *g* being integral with said rolled plate, or the parts may be manufactured in any other manner known to the art, and material appropriate for the purpose may be employed in the construction of the new device.

An essential part of our invention consists in the provision of means on each member for 25 confining the slide against endwise movement after it shall have been moved lengthwise of the member for the purpose of making its pintles *G* engage with the eye-formed end portions *e* of the posts or links *E*. As 30 one of the many forms of locking devices which may be employed for locking the slide in its adjusted position, we have shown a suitable form of locking device in Figs. 8 and 35 9 of the drawings. As represented by the aforesaid figures, the lock *I* is provided with a suitable casing *i*, the latter being equipped with lugs or tenons *i'*, which are passed through suitable perforations in the member, *C* or *D*, whereby the lugs may be clenched 40 against said member for the purpose of securely attaching the casing thereto. The member, *C* or *D*, is provided with a key slot *j*, and within the lock casing *i* is arranged the key post *J*, the latter being slotted for the 45 reception of the key, all as clearly indicated in said Figs. 8 and 9. Within the casing *i* are tumblers *K*, each of which is in the form of a lever with an arm *k*. Said tumblers are shown as pivoted on a post *k'*, and they are 50 held in operative positions by a suitable spring or springs *k''*.

The locking slide *H* is arranged to pass through, and to move within, the lock casing *i*, and said slide is provided with one or 55 more lugs *H'*, the latter being in coöperative relation to the arms *k* of the tumbler levers, see Fig. 8. In some cases we may make the lugs *H'* integral with the slide *H*, by stamping the metal of the slide and bending the 60 stamped portion from the lugs, but, in other instances, we may make the lugs in a separate piece or pieces and fasten the same to the slide, all as will be readily understood by those skilled in the art. It will be understood 65 that the slide *H* of each member may

be moved endwise for the pintles *G* to engage with the end portions *e* of the links or posts, and when thus adjusted, the tumblers *K* are actuated to engage automatically with a lug *H'* of the slide, as shown by Fig. 8, whereby 70 the slide is locked in its adjusted position for holding the links or posts *E* in rigid or permanent relation to the members *C*, *D*. The pages or leaves *B'* of the book cannot be detached from the posts without first opening 75 the lock by the aid of the proper key, and withdrawing the pintles of the slides from engagement with said post, thereby producing a permanent record which cannot be tampered with, altered or mutilated without detection, such construction producing a record 80 which meets all the practical requirements for the safe and secure legal, commercial and mercantile record and account books.

It should be understood that the binder 85 frame is associated with the covers *A*, *B*, in a manner to produce a substantial, strong and efficient structure. The covers *A* and *B* are cut out or recessed on their inner opposing faces, and near their backing *A'*, for the purpose of receiving the members *C*, *D*, said members being embedded in the aforesaid covers so as to lie substantially flush therewith, and being attached thereto by the prongs *g'*, or equivalent fastening devices. 90 For the purpose of giving a neat appearance to the covers, it is preferred to employ the facings *a*, which may be of cloth or other binding material, the same being applied to the covers for the purpose of inclosing the 100 members and the slides. These facings and the covers are cut out or notched at the proper places to provide for convenient access to the locks *I*, and to a means for operating the slides, said facings also exposing the 105 doubled or folded edges of the members so that the keepers may be readily reached in the operation of inserting or removing the posts or links *E*. It is preferred to make each member *C* or *D* with an off-set and slot- 110 ted portions *m*, *m'*, (see Figs. 5 and 6), the slots being indicated at *m'* and the offset at *m*. The slide *H* is provided at one end with a finger piece *o*, the said end portion of the slide working in the keeper *m*, and the finger piece 115 *o* operating in the slot *m'*. It will be understood that the slotted portion *m* of the keeper is exposed through the facing *a*, thus permitting the operator to obtain easy access to the finger piece *o*.

In the manufacture of the new binder the members *C*, *D*, are attached to the covers *A*, *B*, respectively, the keepers or guides *F*, the finger pieces *o*, and the locks *I*, being exposed through the facings *a*, as hereinbefore stated. In assembling the links or posts *E*, the reduced portions *e*, at one end of said posts are fitted in the notches *f* of one member, such as *C*, after which the slide *H* of said member *C* is moved endwise, 125

and the pintles G of said slide are thus moved into engagement with the eyes e^2 at said ends of the links or posts. The endwise adjustment of the aforesaid slide locks the links to 5 said member C, and the slide is itself locked against withdrawal by the tumbler K. The article is now in condition for use, and the pages or leaves B' are slipped over the posts until a desired number of the pages or leaves 10 shall have been supplied. It is now necessary to adjust the reduced portions e^3 at the other ends of the posts in the slots f of the other member D, whereupon the slide H of 15 said member D is moved endwise to force its pintles into engagement with said other ends of the posts, and the said slide is thereupon locked in its adjusted position by the locking mechanism of the member D. It will be observed from this description that 20 the ends of the posts or links E are engaged by the pintles on the slides, which are confined on the respective members C, D, and said slides are in turn held in positions by the locks I, on the aforesaid members, whereby 25 the respective end portions of the links are securely locked to the respective covers of the binder, and it is impossible to detach or remove any one or more of the leaves B, without so mutilating them as to afford a 30 ready means of detection. It will be evident, also, that the custodian of the record or account book may, by the aid of the proper key, release the lock I of either member for the purpose of permitting one of the slides 35 H to be withdrawn, thus releasing the links or posts at one end thereof, whereupon the binder can be opened for the purpose of removing any leaves or adding new leaves to the record, after which the posts E should be 40 again locked to the cover in order to restore the record or account book to a secure and safe condition.

It will be understood that each lock I should be provided with a number of tumbler 45 levers, the number being limited only by the thickness of the cover made for the book. The levers of each set can be made of many different levels, and of a great variety of combinations, so that the lock is proof 50 against picking, for the reason that the arms on the levers must aline accurately before the double lugs H' of the slide will permit said slide to have endwise movement. It is evident that the double prongs and the accuracy required in the operation of the 55 tumblers make it impossible for the lock to be opened without the proper key.

The shoulders e' , at each end portion of the 60 links or posts provide a guide or seat for the pintle G, on the locking side, thus insuring ease and accuracy in the entrance of the pintles into the eyes of the posts. The posts are received into the slots of the members so that the rounded out portions of said 65 posts and the various parts of the binder

frame will aline for closing accurately. We prefer to make each post out of a single solid piece of metal, but it is evident that the posts may be stamped from sheet metal with rolled edges and doubled or folded eyes. 70

Having thus described our invention, what we claim as new and desire to secure by Letters Patent is:—

1. In a binder frame, a supporting member, a plurality of posts, a locking slide supported by said member and having means for engagement with said posts, key-operated locking mechanism on said member, and means movable with the locking slide into and out of coöperative relation to said key- 75 operated locking mechanism.

2. In a binder frame, a supporting member, a slide carried thereby, a plurality of posts adapted for engagement with said slide, key-operated locking mechanism, and a 80 member carried by the slide and movable therewith into and from coöperative relation to said key-operated locking mechanism.

3. In a binder frame, a supporting member, a plurality of posts, a slide having means 90 for interlocking engagement with said posts, means for retaining said slide in position on the supporting member, key-operated locking mechanism carried by the supporting member, and means carried by the slide and 95 movable therewith into and from coöperative relation to said key-operated locking mechanism.

4. In a device of the class described, a member provided at one edge with a guide 100 which is interrupted by a plurality of notches, posts or links each having an eye and shoulders back of said eye, said shoulders being assembled in abutting engagement with the guide of the member and said eyes entering 105 the notches of said member, a slide held in the aforesaid guide and provided with pintles which enter the eyes of the posts or links, and means for locking the slide.

5. In a device of the class described, a 110 member, a plurality of posts, each having an eye, and a guide shoulder, and a slide having pintles adapted to engage with said shoulders and to have interlocking connection with the links or posts.

6. In a binder frame, a supporting plate, a plurality of posts each having an opening at an end thereof, said end portion of the post being provided with a shoulder adjacent the opening, and a slide having pintles which 120 enter the openings of the posts, said shouldered part of each post engaging with said supporting plate.

7. In a device of the class described, a member provided with a longitudinal keeper, 125 the latter having transverse openings, a plurality of posts each of which is reduced at one end, said reduced end of each post forming shoulders on the respective sides of an eye in said end of the posts, whereby the eye formed 130

ends are adapted to enter the aforesaid openings and the shoulders are fitted into engagement with the keeper, a locking member extending lengthwise of said keeper, said locking member being provided with longitudinal pintles which enter the eyes of said posts, and a releasable locking mechanism coöperating with said locking member.

8. In a binder frame, a supporting plate 10 provided with a longitudinal guide, said guide having slots, a slide positioned on said plate exteriorly of the guide thereon, said slide being provided with a web the thickness of which exceeds that of the slide, and said 15 web fitting in the guide of the supporting plate, whereby the slide is retained in position on said plate, a plurality of pintles formed by cutting away the web of the slide, said pintles being slidable across the slots of 20 said guide, and posts adapted for engagement with said pintles.

9. In a binder frame, a supporting member, a lock casing fixed thereto, key-operated locking mechanism within said casing, a slide 25 adapted to move in the lock casing, means carried by said slide and coöperating with said key-operated locking mechanism, and posts adapted for engagement by said slide.

10. In a device of the class described, a 30 plate provided with transverse openings, a slide having a web the thickness of which exceeds that of the slide, said slide being provided, also, with longitudinal pintles, means engaging with said thickened web for confining the slide on the plate, and a plurality of posts each adapted to enter an opening of the plate, whereby the pintles may be thrust into the posts by an endwise movement of the slide.

40 11. In a device of the class described, a member, a chambered casing secured to said member and containing appropriate locking mechanism, a slidable member provided with locking projections arranged to travel in said 45 casing, whereby said locking projections

may be brought into, or moved out of, co-operative relation to said locking mechanism by an endwise movement of the slide, and posts coöperating with the slidable member for interlocking engagement therewith. 50

12. In a device of the class described, a plate, a chambered casing secured to said member and containing a releasable locking mechanism, a slide held on said plate, a locking lug movable with the slide and adapted 55 to be shifted in said casing, whereby the lug may be brought into, or moved out of, coöperative relation to the locking mechanism by an endwise movement of the slide, posts fitted detachably to said plate, and means on 60 the slide for engagement with said posts.

13. In a binder frame, a supporting member, a lock casing fixed thereto, key-operated locking mechanism within said casing, a slide movable through said lock casing, means positioned externally to the lock casing for retaining the slide on said supporting member, projections carried by said slide and adapted to operate within said lock casing, whereby 65 said projections may coöperate with said key-operated locking mechanism, a plurality of posts, and means carried by the slide for engagement with said posts.

14. In a device of the class described, a plate provided at one edge with a longitudinal 75 keeper, said plate having a slot and an offset adjacent to said keeper, a slide held by said keeper in position on said plate, said slide having a finger piece which is adapted to play in the slotted part of the plate, posts coöperating with the plate and the slide, and slide-locking means.

In testimony whereof, we have signed our names to this specification in the presence of two subscribing witnesses.
